EUGENE C. HERTHEL, OF CHICAGO, ILLINOIS, ASSIGNOR TO SINCLAIR REFINING COMPANY, OF NEW YORK, N. Y., A CORPORATION OF MAINE

CRACKING OF OIL

Application filed July 14, 1925. Serial No. 43,467.

This invention relates to an improved method and apparatus for cracking heavier hydrocarbon oils for the production of lighter hydrocarbon oils therefrom. This application is in part a continuation of a prior application filed September 24, 1923, Serial No. 664,502.

In the cracking of heavier hydrocarbon oils in externally heated stills, the heavier oil is heated to a high temperature under pressure and the heat necessary for raising the oil to the cracking temperature is applied directly to the walls of the pressure still, in the case of a shell still, and to the heating tubes in the case of a tube still. As the cracking operation progresses, the formation of carbon and tar constituents takes place and the extent to which the cracking operation can be carried in a single run is limited by the accumulation of such constituents which tend to settle or separate out on the heating surfaces and to form a layer of so-called carbon thereon which interferes with the heat transfer and, unless periodically removed by cleaning, causes overheating of the walls or tubes of the still. To avoid or minimize the danger of such carbon separation on the heating surfaces, the run is commonly stopped before the accumulation of heavy tar constituents becomes too great, or the tar is continuously withdrawn and fresh feed supplied to maintain the charge in a sufficiently fluid condition to permit continued operation for a longer period of time. The danger of such carbon separation and resulting failure of the still walls or tubes is greatest where the intense heat of the furnace gases first comes in contact with the still walls or tubes and where the greatest amount of heating takes place.

According to the present invention, the pressure still itself, whether of a shell or tube type, is protected from the intense furnace heat, and this heat is applied in such a way as to increase the efficiency and capacity of the still.

According to the present invention, I provide an auxiliary heating coil arranged between the firebox and the main heating surfaces of the still and I recirculate part

of the heating gases which have passed over the heating surfaces again over the heating surfaces, including the auxiliary coil, together with fresh products of combustion from the firebox. The recirculation of part of the heating gases assists in protecting the heating surfaces from the intense furnace heat and improves the heating operation, and by arranging the auxiliary coil intermediate the firebox and the heating surfaces of the still proper the temperature of the heating gases is further reduced by the heat absorbed in the auxiliary coil before they come in contact with the main heating surfaces of the still while the heat absorbed in the auxiliary coil is also usefully employed.

The auxiliary coil is used for carrying out a separate cracking operation which may be independent of the cracking operation carried out in the pressure still itself; but which is advantageously combined with the pressure still operation so that the oil subjected to the cracking operation in the preliminary cracking coil is discharged into the main body of oil in the pressure still.

Where the preliminary cracking coil is combined in its operation with the pressure still, the reflux from a reflux tower on the pressure still, or the reflux or heavier ends of the pressure distillate, may advantageously be utilized as charging stock for the auxiliary cracking coil, so that this reflux will be returned through the auxiliary cracking coil to the main body of oil in the pressure still. This reflux oil returned to the still itself may advantageously be admixed with fresh feed which may be utilized for assisting the refluxing action in the reflux tower and then supplied, freed from its lighter constituents and admixed with the reflux, to the auxiliary cracking coil, and subjected to a partial cracking operation therein before it is introduced into the pressure still itself.

By utilizing in the auxiliary cracking coil a fresh charging stock or a mixed reflux and feed, which is free from carbon and tar constituents, the danger of objectionable carbon deposit on the walls of the auxiliary cracking coil is avoided or minimized, even though this cracking coil is subjected to heating gases

at high temperature; while the auxiliary cracking coil is further protected by the recirculation of part of the heating gases and the walls or tubes of the pressure still proper are protected both by the absorption of heat in the auxiliary coil and by the recirculation of part of the heating gases. Overheating of the walls or tubes of the pressure still proper is thus avoided and a milder heating of these walls or tubes is obtained such that the danger of objectionable carbon deposit is reduced and the cracking operation can be carried to a further extent than would otherwise be feasible.

15 In the application of the invention in connection with a pressure still of the shell type, the auxiliary coil may be arranged in the heating flue or in the path of the hottest gases at an intermediate point between the firebox and the still proper, so that the furnace gases which come in contact with the heating surfaces of the still will have been cooled considerably below their initial temperature, while the intense heat of the high temperature products of combustion from the firebox will be absorbed by the oil in the auxiliary cracking coil. Where such a shell still is provided with a reflux tower, or where the distillate therefrom is subjected to refluxing 20 and separation of the heavier constituents therefrom at a lower pressure than that of the still itself, the reflux, either with or without additional feed, can be used as the charging stock of the auxiliary cracking coil and the cracked oil from such coil may then be introduced into the still proper.

Where the auxiliary cracking coil is combined with a tubular cracking still, the coil is similarly arranged between the firebox and the heating chamber or chambers containing the tubes through which the oil is circulated and in which it is heated. The invention is of particular value in connection with such tubular cracking stills for the reason that it 40 protects the tubes from the intense furnace heat and enables a milder heating of the tubes to be obtained. With such a tubular still, the auxiliary cracking coil may likewise be combined to receive the reflux from the still itself or the heavier part of the distillate therefrom and may similarly discharge the partially cracked oil back into the main body of oil undergoing cracking in the tubular still.

45 With either type of still, means are provided for withdrawing part of the heating gases which have passed over the heating surfaces of the still and which have thereby been partially cooled and for returning such withdrawn gases at about the temperature at which they would otherwise escape and admixing them with fresh hot products of combustion from the firebox before the resulting mixture passes over the heating surfaces of the still whereby the fresh heating

gases are tempered. By employing the heating gases at about the temperature at which they would otherwise escape, the tempering is effected without decrease in efficiency and may be accompanied by an increase in efficiency.

The invention is of special value and application in conjunction with pressure stills provided with reflux towers into which the fresh feed is introduced and from which the reflux and admixed feed can be circulated through the auxiliary cracking coil before their introduction into the still proper. The reflux towers may be operated at the same pressure maintained in the pressure still and the refluxed oil, or refluxed oil with admixed feed, circulated through the auxiliary cracking coil, either by gravity or convection circulation or by means of a pump; or the vapors from the pressure still may be reduced to a lower pressure and subjected to a refluxing operation and the heavier refluxed distillate, with or without admixed feed, pumped through the ordinary cracking coil and thence back to the main body of oil in the pressure still.

Where the reflux tower is operated at still pressure, the tower and auxiliary coil may be so arranged relative to each other, and the coil may be so constructed that flow of the oil through the coil and into the still will be obtained by gravity and convection; although this circulation may be effected or increased by means of a circulating pump or other means for increasing the circulation.

The invention will be further described in connection with the accompanying drawings illustrating apparatus embodying the invention and adapted for the practice of the process of the invention, but it will be understood that the invention is illustrated thereby but not limited thereto.

In the accompanying drawings,

Fig. 1 shows a tubular pressure still embodying the invention, the showing being largely conventional and diagrammatic, and partly in section and partly in elevation;

Fig. 2 is a sectional view of one end of the auxiliary cracking coil taken on the line 2-2 of Fig. 3;

Fig. 3 is a top view of the auxiliary cracking coil taken on the line 3-3 of Fig. 2;

While the invention is applicable in connection with cracking stills of different types, yet it is of particular advantage in connection with a tubular cracking still of the character illustrated. This cracking still is of the general construction illustrated in U. S. Letters Patent No. 1,285,200, granted to the Sinclair Refining Company, November 19, 1918, on the application of Edward W. Isom.

The pressure still illustrated in Fig. 1 is made up of the bulk supply tank 1 located away from the heating furnace, the vertical heating tubes 2 arranged in the heating flue

- of the furnace, and circulating pipes 3, 4 and 5 connecting the lower and upper ends of the vertical tubes, respectively, with the bulk supply tank and a circulating pump 6 for 50 circulating the oil from the bulk supply tank through the vertical tubes and back to the bulk supply tank. Arranged above the bulk supply tank is the reflux tower 7 having a series of baffles therein and connected with 55 one or the other or both of these pipes can be shut off when desired. A feed line 35 enters the inlet pipe 24 of the auxiliary coil and permits the direct introduction of fresh feed as it is desired. A tar draw-off connection for use during the operation of the still is shown at 37 and a tar draw-off for discharging the still is shown at 38. 70
- The auxiliary reservoir or tank 28 is shown as located within the bulk supply tank 1, 75 although it is not in open communication therewith except through the pipe connections. This location of the auxiliary reservoir is not essential but is convenient and enables a tank construction to be used which does not need to withstand high pressure as the pressure inside and out is approximately the same. Where the auxiliary tank or reservoir is located within the bulk supply tank it will be evident that valves such as those in the pipes 31 and 36 should have operating handles which extend out through suitable stuffing boxes in the walls of the bulk supply tank. Test cocks (not shown) may be provided for ascertaining the level of the oil in 80 this auxiliary tank or reservoir. 85
- The furnace construction for heating the tubes of the still comprises a firebox 16 suitably heated as by gas or oil burners 17, a vertical flue 18 leading upwardly from the firebox to the upper end of the heating flue containing the vertical tubes, a heating flue having baffles 20 and 21 therein for causing the gases to pass over the vertical tubes in three successive passes and an outlet flue 22 leading to the stack. From a point adjacent to the outlet flue 22 to a point near the lower end of the flue 18, a return connection 41 is arranged for recirculation of part of the heating gases. As illustrated, the connection includes a steam jet blower, although a fan or 90 other suitable forcing means may be used. 95
- Located above the bridge wall 19 and between the vertical flue 18 and the flue containing the vertical tubes 2 is the auxiliary cracking coil 23 having an inlet connecting pipe 24 and outlet pipe 25 leading to the manifold at the upper ends of the vertical tubes. A pipe 26 having a valve 27 therein connects the inlet of the coil to the discharge side of the circulating pump 6. This pipe may be 100 used in starting the still in operation. 105
- An auxiliary tank or reservoir 28 is arranged to receive the reflux and admixed feed from the reflux tower 7 through connection 29. This tank or reservoir has a vent pipe 30 leading back to the reflux tower. The tank or reservoir 28 is also connected through the pipes 31 and 32 to the feed line 24 of the auxiliary coil. A pump 33 is arranged to pump the oil through the auxiliary 110 coil, while the connecting pipe 34 permits circulation by gravity and by convection when the pump 33 is not used. A branch pipe 36 leads from connection 32 to the bottom of the bulk supply tank. The pipes 31 and 36 have control valves therein by which 115
- A feed line 39 is provided for feeding fresh oil to the top of the reflux tower 7. An additional feed line 40 is provided for feeding oil to the bearings of the pump 6. Additional feed can also be introduced through the auxiliary coil through the feed line 35 as above noted. 120
- The auxiliary coil 23 is made up of a series of pipes connected at their ends as indicated in Figs. 2 and 3 and arranged so that the oil flows therethrough in a single pass in a generally upward direction, the flow being thus assisted by convection. 125
- When the still is initially charged, oil may be circulated from the main charge of oil through the auxiliary cracking coil, for example, by closing the valve in the pipe 31 and opening the valve in the pipe 36 when the circulating pump 33 will draw oil from the bulk supply tank 1 and circulate it through the auxiliary coil; or the valve 27 may be opened and oil from the discharge side of the pump 6 may be circulated through the auxiliary coil; or fresh feed may be introduced through the feed line 35. 130
- After the pressure still has been raised to cracking conditions of temperature and pressure, the cracked vapors from the still will rise in the reflux tower 7 and will come in contact with the fresh feed introduced through the line 39 to the top of the tower. By providing a sufficient number of baffles practically all of the feed for the still can be introduced in this way and a pressure distillate approximating a gasoline distillate directly obtained with return of the heavier constituents in the liquid state to the bottom of the reflux tower. This reflux and admixed feed collects in the reservoir or tank 130

28 which, in a still of the type illustrated, may have a capacity for example of about one thousand gallons. From this reservoir the oil is circulated either by gravity or convection or by pump, through the auxiliary cracking coil 23 where it is subjected to the hottest gases from the furnace. The cracked oil is discharged into the top circulating line of the still and is returned to the bulk supply tank. The unvaporized portion of the oil so returned forms a part of the still charge and is circulated therewith through the vertical tubes. It will be evident that the rate of circulation of the oil should be regulated so that a constant supply is provided and so as to maintain a level of oil in the reservoir 28. By introducing all or practically all of the fresh feed into the top of the reflux tower and bringing it into intimate contact with the vapors therein, a constant supply of reflux and admixed feed is provided. Should the reservoir 28 become full the additional reflux and feed will collect in the bottom of the reflux tower and will overflow through the pipe 9 to the bulk supply tank 1.

After the high temperature furnace gases initially tempered by admixture with recirculated cooler heating gases have been reduced in temperature by passage through the auxiliary coil, they then pass over the vertical tubes of the pressure still at a lower temperature and serve to heat these tubes without danger of objectionable overheating. A milder heating and cracking action is thus obtained so that the still charge can be cracked to a further extent without danger of objectionable carbon deposit on the tubes and with the obtaining of heavier residuum from the cracking operation.

In a commercial still of the character illustrated, the auxiliary cracking coil may be made up of four inch pipe and the oil may be circulated therethrough at a regulated rate so that objectionable overcracking will be avoided while effective cracking will nevertheless be obtained, and the resulting cracked oil will then be introduced into the pressure still to admix with the oil and vapors therein.

The operation of the pressure still in this way, with circulation of the feed and reflux through the auxiliary coil and with recirculation of part of the heating gases, and with circulation of the main charge of the still through tubes heated to lower temperatures, gives an increased furnace efficiency with longer running time before it is necessary to shut down for cleaning, and with increased capacity of operation of the pressure still, while also permitting a reduction of pressure tar while under pressure to a higher specific gravity without detriment to the operation.

The higher temperature to which the auxiliary cracking coil is subjected also permits

the cracking therein of kerosene fractions and lighter oils which are more difficult to crack in ordinary pressure stills. Such kerosene fractions may be those produced by the pressure still itself or supplied from another source.

The addition of an auxiliary cracking coil in conjunction with the operation of the pressure still also permits the introduction of an increased amount of feed through the top of the reflux tower and a fractionation of the vapors from the still to much nearer a finished gasoline than is commonly obtained, and this without any difficulty in regular operation.

The entire pressure still system is protected from the intense furnace heat by recirculating a part of the heating gases which have passed over the heating surfaces of the still and admixing this recirculated cooler gas with the fresh heating gases from the furnace before they are passed over the heating surfaces of the still, so that the heating gases used for heating the main charge of oil in the still itself are tempered by the combined effect of the recirculated gases and the action of the auxiliary cracking coil in absorbing the initial intense heat of the heating gases. The recirculation of waste heating gases in this way increases the velocity of flow of the heating gases improving heat transfer and since the waste heating gases are returned at substantially the temperature at which they would otherwise be discharged, both the efficiency and capacity of the pressure still may be further increased.

It will thus be seen that the present invention provides an improved construction and method of operation of pressure stills whereby the intense furnace heat of the heating furnace is utilized in an auxiliary cracking operation where such intense heat is advantageous, and that the cracking operation of the main pressure still is carried out with the furnace gases which have been cooled by their utilization in the preliminary cracking operation.

It will further be seen that the preliminary cracking operation which utilizes the intense heat of the highest temperatures of the furnace may advantageously be combined with the operation of the pressure still utilizing the furnace gases subsequently at a lower temperature such that a milder cracking action is obtained; and that, where these operations are combined, the feed for the auxiliary cracking coil may advantageously be supplied in the form of reflux, or of reflux and admixed feed from the reflux tower of the pressure still.

The temperature and pressure employed in the carrying out of the process and in the operation of the apparatus can be varied with different characters of charging stock. Where ordinary gas oil is employed in the

main pressure still pressures of around 90-125 lbs. may be employed; while with lighter oils, higher pressures may be used, for example of around 300-325 lbs. The 5 pressure maintained in the auxiliary cracking coil may be the same as that in the pressure still or only enough higher to cause the desired circulation; or the auxiliary cracking coil may be maintained at a considerably higher 10 pressure and the pressure reduced in case the cracked oil is to be discharged into the pressure still at a lower pressure.

I claim:

1. The improvement in the operation of externally heated pressure stills, which comprises heating a body of oil to a cracking temperature by positively circulating the oil over externally heated surfaces in the pressure still and circulating heating gases from 20 a firebox externally over the heating surfaces of the pressure still, forcing tar-free oil once only through a separate cracking coil interposed between the heating surfaces of the pressure still and the firebox and thence directly into the pressure still, and recirculating heating gases which have passed over the separate cracking coil or the heating surfaces of the pressure still and admixing them with the heating gases from the firebox before the 30 fresh heating gases pass over the heating surfaces of the pressure still.

2. The improvement in the operation of externally heated pressure stills, which comprises heating a body of oil to a cracking temperature by positively circulating the oil over externally heated surfaces in the pressure still and circulating heating gases from a firebox externally over the heating surfaces of the pressure still, subjecting the 40 vapors from the pressure still to a refluxing operation and forcing the reflux therefrom once only through a separate cracking coil interposed between the heating surfaces of the pressure still and the firebox and re-circulating heating gases which have passed over the heating surfaces of the pressure still and admixing them with the heating gases from the firebox before the fresh heating gases pass over the separate cracking coil or the heating 50 surfaces of the pressure still.

3. The improvement in the operation of externally heated pressure stills, which comprises heating a body of oil to a cracking temperature by positively circulating the oil over externally heated surfaces in the pressure still and circulating heating gases from a firebox externally over the heating surfaces of the pressure still, subjecting vapors from the pressure still to a refluxing operation and forcing the reflux therefrom in admixture with fresh oil once only through a separate cracking coil interposed between the heating surfaces of the pressure still and the firebox and thence directly into the pressure still, 60 and re-circulating heating gases which have

passed over the heating surfaces of the pressure still and admixing them with the heating gases from the furnace before the fresh heating gases pass over the separate cracking coil or the heating surfaces of the pressure 70 still.

4. In the operation of externally heated pressure still systems in which a charge of oil is heated to the cracking temperature by circulating the oil from a bulk supply tank through a heater and back to the bulk supply tank by circulating heating gases from a firebox in indirect heat exchanging relation with the oil in the heater, the improvement which comprises passing tar-free oil once only through a separate heating coil interposed between the heater and the firebox and into the pressure still system, and re-circulating heating gases which have passed in heat exchanging relation with the oil in the heater and admixing them with the heating gases from the firebox before the fresh heating gases pass in heat exchanging relation with the oil in the separate heating coil or in said heater.

5. An apparatus for cracking heavier hydrocarbon oils for the production of lighter hydrocarbon oils therefrom, comprising a circulatory cracking still and means for positively circulating oil over the heating surfaces thereof, a furnace for heating the same, a single pass auxiliary cracking coil interposed between the fire box of the furnace and the heating surfaces of the pressure still arranged to discharge into the still, means for independently circulating tar-free oil once only through said auxiliary cracking coil and thence directly to the still, and means for re-circulating heating gases which have passed over the heating surfaces of the still and admixing them with heating gases leaving the fire box in the furnace.

In testimony whereof I affix my signature.
